UNITED STATES PATENT OFFICE.

LESTER KYLE ALDRICH, OF SIDNEY, OHIO.

HOLDDOWN AND REGISTER FOR AUTOMATIC FEEDERS.

Application filed June 2, 1927. Serial No. 196,028.

The invention relates to a hold down and register for automatic feeders.

In feeding paper on an automatic register, one of the most difficult problems is to prevent the second sheet from creeping as the top sheet is pulled off the pile.

Irrespective of how much air is used to flutter the sheets for separation, the drag is apparent and will pull the next sheet forward against the front abutment. This causes the front edge of the said sheet to become bent downwardly thereby causing a clogging or stumbling of the sheet when the suction nozzle attempts to lift it up and take it off the pile. This drag is particularly apparent on large sheets or sheets with heavy forms requiring heavy ink.

The object of the present invention is to provide a simple, practical and efficient device adapted to be readily applied to various types of automatic feeders and capable of stopping the forward drag of the second sheet and of then moving the said sheet backwardly to its former position in perfect register against the rear abutment.

The present invention solves a very difficult problem that has heretofore existed in the feeding of paper at a high rate of speed. Heretofore in automatic feeders trouble has always been experienced with the second sheet creeping. The top sheet was pulled forward so quickly, and to secure any high degree of speed the action is so extremely fast, that as the result the following sheet had a tendency to creep forwardly from one-eighth to three-fourth of an inch. Just as the suction nozzle drops down to pull off a sheet and pulled forward to the press folder or other machine, the sheet would stumble or clog. The present invention entirely eliminates this difficulty and checks the forward movement or creeping incident to the drag on the second sheet and then moves the second sheet into perfect register.

With these and other objects in view, the invention consists in the construction and novel combination and arrangement of parts hereinafter described, illustrated in the accompanying drawings and set forth in the

claims hereto appended, it being understood that various changes in the form, size, and minor details of construction, within the scope of the claims, may be resorted to without departing from the spirit of the invention or sacrificing any of the advantages thereof.

In the drawings:—

Figure 1 is a side elevation of a portion of the feeder illustrating the manner in which the front edges of the sheets are bent downwardly against the front abutment causing the sheets to stumble.

Fig. 2 is a side elevation of a portion of the automatic feeder provided with a hold down and register constructed in accordance with this invention, the top sheet being clear of the device and the latter being engaged with the second sheet.

Fig. 3 is a similar view, the device being at the limit of its downward movement, the second sheet being moved into register against the rear abutment.

Fig. 4 is a side elevation showing the opposite side of the device, the pivoted arm and paper engaging tip being in section.

Fig. 5 is a transverse sectional view of the device.

Fig. 6 is a detail view of the connections between the device and its actuating mechanism.

In the accompanying drawings is illustrated the preferred embodiment of the invention, but the claims define the scope of the latter.

In Fig. 1 of the drawing is illustrated a portion of the automatic feeder shown and described in Patent No. 1,546,184, granted to me July 14, 1925, and at the front abutment 1, the second, third and fourth sheets of the stack or pile 2 are shown with their front edges 3 bent downwardly against the front abutment. This downward bending of the said sheets is caused by the drag resulting from the feeding of the top sheet by the suction nozzle 4 of the automatic feeder of the said patent. The device of the present invention which checks this forward drag of the sheets and returns the second sheet to

its initial position in proper register with the rear abutment 5 is illustrated as applied to applicant's automatic feeder of the said patent, but it may be applied to various 5 other automatic feeders. The device comprises in its construction a vertical support 6 consisting of a post or body arranged in upright position and preferably rectangular in cross section and provided at its upper 10 portion with a transverse opening 7 for the reception of a shaft or rod 8 upon which the body or support 6 is mounted and to which the same is secured by a clamping screw 9 mounted in a threaded opening 10 in the upper 15 portion of the body 6. The threaded opening 10 extends from the upper end of the body to the transverse opening 7 and the inner end of the clamping screw engages the transverse rod 8 and firmly secures the body 20 to the rod in proper adjustment.

The body 1 is provided preferably at the center with a transverse bearing opening 11 for the reception of a horizontal pivot 12 of an arm 13 of approximately L-shape extending 25 downwardly and rearwardly from the pivot and carrying at its rear end a threaded stem 14 having a sheet engaging tip 15 at its lower end. The body 6 and the arm 13 may be constructed of any suitable material and 30 the pivot 12 which in the drawings is shown integral with the arms 13 may be constructed in any desired manner and it is detachably secured in the bearing opening 11 by a cotter pin 16 arranged in a suitable perforation 17 of the pivot. The washers 18 are preferably arranged at opposite sides of the body, one of the washers being arranged between the arm and the body and the other washer between the body and the cotter pin.

40 The approximately L-shaped arm 13 which extends downwardly and rearwardly from the pivot 12 at an acute angle to the upper face of the stack or pile 19 rests against a stop pin 20 of the body when the device is elevated and out of contact with the paper. The stop pin 20 is mounted in the lower portion of the body but any other suitable form of stop may be employed as will be readily understood. The pivoted 45 arm bears against the stop 20 at the rear side thereof at a point intermediate of the ends of the pivoted arm and the said stop limits the downward and forward swing of the arm and maintains the arm normally in the 50 position illustrated in Fig. 2 of the drawing when the device is elevated out of contact with the stack. The rear end of the arm is enlarged and provided with a threaded opening 21 to receive the threaded stem 14 55 which is provided in its upper end with a groove 22 for the reception of a screw driver or other tool for adjusting the stem and the tip and the stem is maintained in its adjustment by a lock nut 23 which is preferably 60 in the form of a thumb nut.

The tip 15 which is mounted on the lower end of the stem is secured to a smooth portion thereof and it preferably consists of a sleeve of rubber tapered upwardly as shown and projecting below the stem to form a 70 socket or cup-shaped paper engaging portion whereby it is adapted to effectively creep the second sheet and stop the forward movement of the same and also to maintain its grip on the second sheet while moving the 75 latter back to its initial position in perfect register against the rear abutment 5.

The rod or shaft 8, when the device is applied to the automatic feeder of the said patent is movable vertically and is connected with a lever 25 which is the lever which operates the ratchet of the stack elevating mechanism of the said patent. The body may be connected with various other automatic feeders and while it is shown operating in a vertical arcuate path of movement in the accompanying drawings, it will function if the up and down movement is parallel and it may be operated from any available movable part of a feeder and one 80 or more of the devices may be employed for checking the drag on the second sheet and for returning it to its initial position.

The rod 8 which swings in a vertical arc to raise and lower the hold down and register is adjustably mounted at one end in a transverse opening 26 of a lever 27 fulcrumed on a bracket arm 28 of the frame of the feeder. The lever 27 is fulcrumed intermediate of its ends on a suitable pivot 29 and it extends above and below the pivot and is provided at its lower arm or portion with a laterally extending transversely disposed pin 29' which operates in a slot 30 of a vertical link 31. The link 31 is secured 95 to and carried by said lever 25 and in its oscillation operates the hold down and register device in proper timed relation with the feeding mechanism of the machine. The outwardly extending laterally projecting pin 29' abuts against a frame to limit its upward movement and it is swung downwardly by a link or connection 31, the upper wall of the slot 30 thereof engaging the said pin to effect this movement. The slot permits 100 the lever 25 and the arm to move upwardly after the pin 29 has engaged the frame and reached the limit of its upward movement so that the continued upward movement of the link 31 will not affect the hold down and register device. The register rod is secured 105 in the opening 26 by a clamping screw 32. It will be noted that at the time the rubber tip of the device comes in contact with the paper the register shaft or rod is practically 110 in a horizontal position to prevent any side movement of the sheets from the arcuate movement of the device.

In sheet 2 of the accompanying drawings, the suction nozzle 4 is shown pulling the top 115

sheet off the stack and the second sheet is dragged. The pull down and register is descending and just as the top sheet has passed the vertical line of travel and is clear of the rubber tip, the latter engages the second sheet and retards the forward movement. This occurs when the device has completed approximately three-fourths of its downward movement and one-fourth of the downward travel is to be completed. This further downward movement of the device operates to move the pivoted arm and the rubber tip rearwardly in a horizontal direction as indicated by the arrow in Fig. 2 of the drawing, thereby returning the second sheet to its initial position in proper register against the rear abutment 5. As the pivoted arm is arranged substantially at an acute angle to the face of the second sheet any drag or tendency to move the second sheet forward will cause the rubber tip to grip the sheet firmly and the final portion of the downward movement of the device moves the second sheet rearwardly into register. The rubber tip is automatic in its gripping action and the adjusting screw is adapted to raise or lower the tip and enables the tip to descend and engage the second sheet just as the tail of the top sheet is clear of the device. The threaded stem and the lock nut provides a final adjustment for accomplishing this result.

What is claimed is:

1. A hold down and register for automatic feeders comprising a body movable upwardly and downwardly to clear the top sheet of a stack, means extending rearwardly from the body and carried by the same for engaging the second sheet of the stack when the top sheet is clear of the device, and means operated by the downward movement of the device for moving the said second sheet rearwardly to its initial position in perfect register.

2. A hold down and register including a body movable upwardly and downwardly to clear the top sheet of a stack, a member extending rearwardly from the body and carried by the same in the upward movement thereof and provided with means for engaging the second sheet, and means for causing the said member to move rearwardly during a portion of the downward movement of the said body to return the second sheet to its initial position in register.

3. A hold down and register for automatic feeders comprising a body movable upwardly and downwardly, an arm pivotally connected with and carried by the body and provided with means for engaging the second sheet of the stack and arranged to be moved rearwardly by the downward movement of the body whereby the second sheet is returned to its initial position in register,

said arm having adjustable means for controlling the amount of movement imparted to the said second sheet.

4. A hold down and register for automatic feeders comprising a body movable upwardly and downwardly, an arm pivotally connected to the body and extending rearwardly therefrom and provided with paper engaging means adapted to engage the second sheet of a stack and means for limiting the downward and forward movement of the arm with respect to the body, said arm when engaged with the second sheet of the stack being moved rearwardly by the body during a portion of the downward movement thereof.

5. A hold down and register for automatic feeders comprising a body, an arm pivoted to the body and extending downwardly and rearwardly from the body, said body being provided with a stop for limiting the relative downward movement of the arm, and means carried by the arm for engaging the second sheet of a stack, said arm being moved rearwardly during a portion of the downward movement of the body to return the second sheet to its initial position.

6. A hold down and register for automatic feeders comprising a body, an arm pivoted to the body and extending downwardly and rearwardly from the body, said body being provided with a stop for limiting the relative downward movement of the arm, and an adjustable stem mounted on the arm and provided with an elastic tip for engaging the second sheet of a stack.

7. A hold down and register for automatic feeders comprising a body, an arm pivoted to the body and extending downwardly and rearwardly from the body, said body being provided with a stop for limiting the relative downward movement of the arm, and a threaded stem engaging the threaded opening in the arm and provided at its lower end with an elastic tip for engaging the second sheet of a stack, and means for securing the stem in its adjustment.

8. The combination of a feeder including a member movable upwardly and downwardly, a lever fulcrumed on the machine and arranged to swing transversely thereof, a transversely disposed rod carried by the lever, a hold down and register device mounted on the rod and movable vertically in an arc, and means carried by the said member for oscillating the lever.

9. The combination of a feeder including a member movable upwardly and downwardly, a lever fulcrumed on the machine and arranged to swing transversely thereof, a transversely disposed rod carried by the lever, a hold down and register device mounted on the rod and movable vertically in an arc, and a pin and slot connection be-

tween the member and the lever for oscillating the lever.

10. The combination with a feeder having a vertically movable lever, a transversely movable lever mounted on the machine and provided with a laterally projecting pin, a connection carried by the vertically movable lever and having a slot receiving the said

pin for actuating the transversely movable lever, a hold down and register device, and 10 means for connecting the same with the transversely movable lever.

In testimony whereof I affix my signature.

LESTER KYLE ALDRICH.
